UNITED STATES PATENT OFFICE

2,633,852

CHANGEABLE SIEVE HULLER

Elmer H. Lupton, Baltimore, Md., assignor to The Sinclair-Scott Company of Baltimore City, a corporation of Maryland

Application July 10, 1950, Serial No. 172,966

2 Claims. (Cl. 130—30)

1

This invention relates to hulling equipment for leguminous vegetables and more particularly to the class of machines that separates hulls from beans or peas, to discard the first and selectively deliver the last to predetermined locations for packing or delivery.

This invention is similar in general structure and principle to that made the subject matter of the patent application, Serial Number 100,153, filed in the United States Patent Office, but constructed with improvements that add certain practical features not attained in previous machines of this nature.

One of the objects of this invention is to provide a new and improved hulling machine for beans and peas, that will have its sorting screens made readily removable and otherwise less difficult to handle for maintenance work.

Another object of the invention is to provide a new and improved hulling machine for beans, peas and the like, that will be capable of handling the material to be processed therein, without stressing its sorting screens excessively or causing uneven rotation or wobbling.

A further object of the invention is to provide a new and improved hulling machine that will be designed to prevent packing of the hulls in structural corners of the device during its use.

An additional object of this invention is to provide a new and improved hulling machine for beans, peas and the like that will process the vegetables effectively, in a smooth and continuous manner.

Other objects of the invention will become apparent as the invention is more fully described.

For a better understanding of the invention and the objects thereof, reference is made to the accompanying drawings, which in conjunction with the following description, illustrate a particular form by way of example, while the claims emphasize the scope of the invention.

In the drawings:

Figure 1 is a perspective view of a hulling machine for peas in the pod, embodying this invention, its housing being partly broken away to show its interior construction;

Figure 2 is a sectional view of the machine taken along the longitudinal center of drum;

Figure 3 is a sectional view taken on line 3—3 of Figure 2; and

Figure 4 is an exploded view of the spider, runner support, screens, channels and U member.

Similar reference characters refer to the same parts throughout the drawings.

In the construction indicated, a rotating screen

10 of boxed-in form and hexagonal cross-section is used for whole peas in their pods to be placed therein to be hulled. It has an entrance or feed spider 11 at one end, including an orifice 12 through which the peas in their pods are introduced. This spider 11 has a centrally located sleeve 13 arranged externally to act as a bearing to revolve in an outer bearing 14 and internally to receive a rotating shaft 15. The spider 11 is preferably dished inwardly to assist in feeding the pods into the screen to be hulled.

At the opposite end of the screen 10, a discharge spider 21 is attached, but is left partly open at 16 to allow the hulls or pods to be discharged therefrom after the peas have been removed from the screen. The screen 10 includes a series of six perforated panels 17, with numerous holes 18 through them for the passage of any loose peas that align with them. These peas pass through the panels and are passed to a suitable conveyor 45 underneath to be taken away as required or necessary from time to time. The panels 17 are provided with edges 19 bent angularly upwardly.

The screen structure has six longitudinal runners 20 extending from the spider 11 to the spider 21 and fastened at the ends by bolts 22 thereto. The runners 20 are preferably made of pipe with holes 52 therein, and form a rigid frame structure for the screen. They support the panels 17 with their edges 19 sticking upwardly, when channels 23 having holes 53 therein are laid longitudinally thereon and secured by the bolts 24 passing through them. The channels 23 are positioned on the outside of the screen. An additional U-member 25 is placed on the underside of the runner structure to contact each pipe 20. It is held by the same bolts 24 and wing nuts 54 and clamps the parts in between. The runner structure forms the framework of the screen, and with the perforated panels 17 thereon, makes a very substantial screen, of hexagonal contour. The shaft 15 runs axially through the interior space of the screen and is held in the internal bearing 26 in the sleeve 13 at one end, and in a similar bearing 27 in a sleeve 28 extending similarly from the discharge spider 21. Six paddles 46, 47, 48, 49, 50 and 51 are mounted on the shaft and preferably spaced 60 degrees apart in a helical manner as noted in Figures 2 and 3. They are so mounted that they tend to drive the vegetable material in the screen from the feed orifice 12 towards the discharge opening in the spider 21. The paddles are built in the form of spokes and with blades 29 predeterminedly pitched and in 55 T-form therefrom and designed to open the hulls

of the peas or beans between their peripheral edges and the inner surface of the screen and runners or U-members so they will release the peas from the pods without injuring them. This is done as the pods pass by the paddles. When the shells or hulls are empty they pass along and through the discharge.

The sleeves 13 and 28 are journalled in the bearings 14 and 30 respectively in a frame 35 that supports the screen 10 and the mechanism that operates it. The frame is provided with legs 36 that support the machine off the floor. The screen is rotated through the use of sprocket gear 37 mounted on its sleeve 28 and driven by another sprocket gear 38 actuated by a transmission chain 40 driven by a motor 39. The shaft 15 is also rotated by the motor 39 through the use of sprocket gears 41 and 55, and transmission chain 56. The shaft 15 and paddles are rotated about 10 times faster than the screen, but they preferably run in the same direction.

The operation of the device does not seem to require further detailing. The features most conspicuously noticeable in the machine, include those that give the screen a tumbling action by reason of the hexagonal shape; the non-clogging and lifting action performed by the extending U-members 25; the propelling action of the paddles, the convenient effective and expeditious arrangement for attaching or detaching the screen plates, the covering of all moving parts to make it safe, and the neat, compact and attractive design that it provides. A supply storage 43 is connected to the housing 57 and through a suitable duct pours the peas into the screen through the orifice 12 as required.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. In a hulling machine, a generally polygonal screen, said screen including removable sections, and means for securing the adjoining ends of said sections, said means comprising turned up extensions at the ends of the screen sections, a set of longitudinal channels encompassing the turned-up extensions, pipes extending from end to end of the screen adjacent and beneath the turned-up extensions, a second set of longitudinal channels encompassing the said pipes, both sets of channels having their sides aligned in the same direction, bolts extending through the webs of both sets of channels and through said pipes to secure these elements together.
- 5 2. A hulling machine comprising a polygonal screen, said screen including removable sections, each of said sections having turned-up extensions, means for assembling adjoining sections comprising longitudinal channels enclosing the turned-up extensions, runners extending from end to end of the screen adjacent and beneath the turned-up extensions, a second set of longitudinal channels encompassing the said runners, both sets of channels having their sides aligned, 10 bolts extending through the webs of both sets of channels and through the runners to secure these elements together, a shaft running longitudinally through the screen, a plurality of paddles helically mounted on said shaft for propelling and opening of the pods being hulled and means for rotating said shaft.
